UNITED STATES PATENT OFFICE.

JOSEPH GAWLIK, OF MILWAUKEE, WISCONSIN.

HORN FOR PHONOGRAHS.

Application filed January 26, 1922. Serial No. 531,980 1/2.

To all whom it may concern:

Be it known that I, JOSEPH GAWLIK, a citizen of the United States, residing at 608 Lincoln Avenue, in the city of Milwaukee, 5 county of Milwaukee, and State of Wisconsin, have invented new and useful Improvements in Horns for Phonographs, of which the following is a specification.

This invention relates to phonograph 10 horns.

Objects of this invention are to provide a phonograph horn in which a natural rendition of the original tone qualities is approximated in which the harsh offensive 15 sounds, such as that due to scratching or scraping, are not reproduced in the same volume as the sonorous musical sounds recorded, and in which means are provided whereby the amplification of the sound is 20 attained in such a manner that the full resonant characteristics are secured.

An embodiment of the invention is shown in the accompanying drawing, in which—

Figure 1 is a longitudinal, sectional view 25 of the horn, such view corresponding to a section on the line 1—1 of Figure 2.

Figure 2 is an end view of the horn with a portion broken away.

Figure 3 is an enlarged fragmentary plan 30 view of a portion of the inner wall of the horn.

Referring more in detail to the drawing, it will be seen that the horn comprises a contracted neck portion 1 and a flaring 35 outer, or end portion and that the horn is curved and is gradually tapered from the contracted neck to the outer end. The horn comprises an upper, curved, flaring top wall 2, substantially vertical side walls 3 and a 40 curved, flaring bottom wall 4. An auxiliary wall 5 is provided, which conforms to one of the main walls of the horn, such as the lower wall 4, as illustrated in the drawing. This auxiliary wall 5 is similarly curved 45 and flaring and is spaced a slight distance from the wall 4 and towards the neck portion gradually approaches such wall. It is provided with an end wall 6 adjacent the neck portion, which completely closes that 50 end of the chamber between the walls 4 and 5.

Openings are provided through the auxil-

iar wall 5 adjacent its forward portion and in the form shown, may comprise a pair of scroll like openings 8 symmetrically arranged with respect to a center line. 55

It will be seen that the auxiliary wall 5 provides, in effect, a sound board and that a resonant chamber of gradually decreasing cross sectional area is provided between the auxiliary and the main wall. In this manner, the auxiliary wall is free to vibrate and to resonate to several different tones and this action is enhanced by the resonant cavity formed between the walls. It is also to be 60 noted that the higher pitched notes are reinforced by the relatively shallow resonant chamber and that the lower pitched notes are reinforced by the vibrating sound board 65 5. In addition to this, the sound board, it 70 will be noted, is of different width; that is to say, is of a gradually decreasing width as the neck of the horn is approached. In this manner, such sound board may resonate to widely different notes and will thus enhance 75 the artistic reproduction of a piece.

It is further to be noted that the horn is of substantially the same general contour as the commercial horns and it, therefore, becomes apparent that it is not necessary to 80 needlessly encumber a phonograph with unsightly parts, but that this horn may be employed in the usual types of phonographs without alteration.

I claim:

A phonograph horn comprising a body portion having a downwardly extending neck and a flared main portion extending outwardly therefrom, said neck and flared portion having vertical side walls and being 85 gradually curved at their upper and lower walls, and an auxiliary wall spaced from said lower wall and conforming approximately to the curvature of said lower wall, said side walls extending downwardly and 90 joining said auxiliary wall, said bottom wall having a plurality of scroll slots therein adjacent its outer end, the compartment 95 formed between the auxiliary wall and the bottom wall being the sole auxiliary compartment, all of the parts of said horn being 100 rigid.

JOSEPH GAWLIK.
